Inventor:

Frank M. Wojtalewicz

UNITED STATES PATENT OFFICE

114,854

DESIGN FOR A CARD HOLDER

Frank M. Wojtalewicz, Chicago, Ill.

Application January 23, 1939, Serial No. 82,547

Term of patent 3½ years

To all whom it may concern:

Be it known that I, Frank M. Wojtalewicz, a citizen of the United States, residing in the city of Chicago, in the county of Cook and State of Illinois, have invented a new, original, and ornamental Design for a Card Holder, of which the following is a specification, reference being had to the accompanying drawing, forming a part thereof.

In the drawing:

Fig. 1 is a side elevational view of a card holder showing my new design; and

Fig. 2 is a front elevational view thereof.

I claim:

The ornamental design for a card holder, substantially as shown.

FRANK M. WOJTALEWICZ.
